ITEM COUNTER FOR COMPUTING MACHINES

Robert E. Boyden, Los Angeles, and Wharton A. Parsons, Glendale, Calif., assignors to Clary Multiplier Corporation, Los Angeles, Calif., a corporation of California

Application May 9, 1947, Serial No. 747,018

12 Claims. (Cl. 235—60)

1

The present invention relates to adding and listing machines, cash registers and the like and has particular reference to item counting and/or tax computing devices for such machines.

As is well known, it is often desirable in using machines of the above type, to obtain the total number of the items which are listed in any one group or for any one customer. Generally, this is accomplished by providing a counter section into which the unit 1 is added in each entry of the value of an item into the machine. Upon a totalling operation, the total accumulated on the item counter section is totalled out along with the normal totalling of the accumulated item values, these totals being printed side by side on the paper tape. However, several problems arise in connection with certain types of operations which materially complicate the arrangement control of the item count. For example, it may be desirable to subtract amounts from the accumulator or accumulators without adding or subtracting such item from the counter section. Again, it is often desirable to enter a federal, state or city tax or the like which is due for a lot or quantity of items in order to determine the total without entering such item on the counter. Also, it is undesirable to accumulate item counts when false entries are made in the machine due, for example, to inadvertent adding operations occurring when no values are set up on the keyboard.

Accordingly, one object of the present invention is to provide an item counting device which will accumulate a count of certain added items only.

Another object is to render the item counting device ineffective to count the entry of tax, duty or the like items.

A further object is to print the total of a number of items being listed along with the total of the values of such items while eliminating the printing of the unit 1 for each item during the printing of the value of such item.

A further object is to disable the item counting device when no item is entered in the keyboard.

A further object is to eliminate any load on the item keys or on the racks in sensing the entry of an item in the machine.

A further object is to reduce the amount of revision necessary in order to incorporate an item counting feature in a standard adding machine.

The present invention accomplishes its functions with a simple revision of the machine and for this purpose certain orders of the accumu-

2

lator and printing mechanisms are reserved for item counting. The entry of the unit 1 in the item counting section of the accumulator is effected by a tens transfer operation so that the same mechanism that is used to transfer tens is also utilized to effect an item count.

The manner in which the above and other objects of the invention are accomplished will be readily understood on reference to the following specification when read in conjunction with the accompanying drawings, wherein:

Fig. 1 is a plan view of an adding machine embodying the present invention.

Fig. 2 is a longitudinal sectional view, with parts broken away, of the machine.

Fig. 3 is an enlarged fragmentary front view of part of the control means for enabling zeros to be printed to the right of the lowest significant digit of the value being printed and for segregating the item counter section from the item value printing section.

Fig. 4 is a transverse sectional view through the accumulator unit and is taken substantially along the line 4—4 of Fig. 6.

Fig. 5 is a transverse view similar to that of Fig. 4, such showing a tens transfer actuator in condition to effect a tens transfer in an additive direction.

Fig. 6 is a fragmentary front view illustrating a portion of the accumulator.

Fig. 7 is a longitudinal sectional view illustrating the clutch and symbol printing controls.

Fig. 8 is a longitudinal sectional view illustrating the accumulator positioning controls.

Fig. 9 is a longitudinal sectional view illustrating the item counting device controls.

Fig. 10 shows a sample tape as printed by the mechanism of the present invention.

The particular embodiment of the invention disclosed herein is adapted to the well known commercially available Clary adding machine which is disclosed and claimed in the copending application of R. E. Boyden, S. N. 582,553, filed March 13, 1945, while the particular accumulating mechanism of the Clary adding machine is disclosed and claimed in the copending application of E. P. Drake, S. N. 582,554, filed March 13, 1945, now patent number 2,472,696, issued June 7, 1949.

Since the machine to which the present invention is applied is generally disclosed in the above mentioned Boyden and Drake applications and is found in the commercially available Clary adding machine, only those portions of the machine which relate to the present invention will be dis-

closed in detail. Reference is had to said applications for a disclosure of a complete adding machine including mechanisms not specifically disclosed herein. However, it is to be understood that the invention is not limited to the machine disclosed in said applications.

Referring to Fig. 1, the machine includes a series of banks of amount keys 9 on which the various amounts to be entered in the machine are set. Arranged around the amount keys are a series of control keys and bars including a clear key 16 for releasing any erroneously depressed keys 9, a repeat bar 15, two add bars 10 and 11, a subtract bar 13, a tax entry bar 14 for adding tax values, etc., into the machine, a subtotal bar 18, and a total bar 17. The construction and arrangement of the keyboard formed by the above indicated keys and control bars is disclosed and claimed in the following copending applications: Ciary and Boyden, S. N. D. 123-664, filed November 10, 1945, now Patent Number Des. 148,453, issued January 27, 1948, and Boyden, S. N. 719,244, filed December 30, 1946, now Patent Number 2,495,832, issued January 31, 1950.

General construction

Each order of the machine comprises nine depressible amount keys 9 arranged to differentially control the extent of movement of an aligned rack 19 from its home or zero position shown in Fig. 2. Each key 9, when depressed, positions its stem 29 in place to arrest a coacting shoulder 79 on the associated rack when the latter has been advanced forwardly (to the left in Fig. 2) a number of increments equal to the value of the depressed key. Also, each key, when depressed, acts through devices disclosed in said Boyden application, S. N. 719,244, to retract a zero stop 42 from in front of one of the shoulders 79. However, as is common practice in adding machines of this type, there is no row of amount keys provided for the arithmetically highest order of the machine.

The racks 19 are guided through their fore and aft movement by shafts 70 and 81, slidably fitted within slots 730 and 86, respectively, in each rack.

For the purpose of differentially driving the racks, the shaft 70 is moved sideways, by means not shown, along slots 73 in machine side frames 24 and is yieldably connected to each rack by pairs of opposed drive elements 76 carried by the shaft and having rollers 75 which normally engage in lateral depressions formed at the closed end of the slot 730 in the respective rack. A spring 77 urges the elements 76 to normally hold the rollers 75 in the depressions in slots 730 until the respective rack is arrested by the zero stop 42 or by a depressed key or by an accumulator element as will appear hereinafter.

The aforementioned yieldable drive means is disclosed and claimed in the copending application of Boyden, S. N. 718,706, filed December 27, 1946, now Patent Number 2,490,200, issued December 6, 1949.

Each rack is provided with a pair of rack gear sections 83 and 84 extending on diametrically opposite sides of ordinarily arranged accumulator element gears 85. During adding or subtracting operations the various accumulator gears 85 will be raised or lowered, respectively, into mesh with the associated rack gear sections so that they will be rotated in the appropriate direction during the forward movement of the racks while,

during the return of the racks, the gears 85 will be held in their neutral positions illustrated in Fig. 2. During totalling operations, the gears 85 are held in mesh with the lower rack gear sections 84 during forward movement of the racks only, while during sub-totalling operations the gears are held in mesh with the rack gear sections 84 during forward and return movement of the racks.

10 The various values registered on the racks 19 during either item entering or totalling operations are printed on a paper tape 8 (Figs. 2 and 10) which is fed from a roll (not shown), around a platen 12 to a printing point at which the values are printed thereon.

15 The printer comprises a series of numeral printing dials 135, one for each rack 19. Each dial has thereon a series of type ranging from 0 to 9 and these dials are so connected to the associated racks that they will print the digit corresponding to the value of the key depressed in the associated order or to the numerical position to which the rack is moved in its forward stroke. It should be noted at this point that the 20 two highermost dials, racks 19 and gears 85 are reserved to form the item count section.

25 Each dial 135 is rotatably mounted on a separate lever 136 which is loosely keyed on a printer control shaft 137 and is spring urged clockwise by a tension spring 138. A gear 139 fixed to each dial is permanently meshed with a gear 140 also rotatably mounted on the associated lever 136. Except during the printing operation, the levers 136 are held in their positions illustrated 30 in Fig. 2 wherein the gear 140 meshes with an aligned one of a series of idler gears 141 rotatably mounted on a cross shaft 142. The latter idlers are continuously entrained with respective ones of the drive racks 19 through a series of pinion assemblies 176, the details of which are not deemed necessary to disclose herein.

35 During the printing phase, and after the racks have digitized the printer and the accumulator, 40 or have been positioned under control of the accumulator, the printer control shaft 137 is rocked clockwise by means not shown, permitting springs 138 to rock the printer arms 136 of certain of the dials 135 and thus carry the printing dials 45 forward into contact with a printing ribbon 144 and the paper strip 8, whereby to print the number registered on the dials onto the paper at the printing station.

45 Means are provided to prevent printing of zeros to the left of the highest significant digit in a value being printed, except the total of an item count as will be explained hereinafter, while enabling all of the zeros to the right thereof to be printed. For this purpose, a latch 152 (Figs. 50 2 and 3) is provided adjacent each lever 136 and is journalled on a cross rod 153 extending through cams slots 154 in the various gears 141. The latches 152 are urged clockwise by springs 155 and are provided with ears 157, each adapted 55 to normally overlie a foot 158 extending forwardly from the aligned lever 136. A roller 159 on each latch rides in the cam slot 154. When the associated idler 141 and printing dial 135 are retained in zero position the contour of the cam 60 slot enables the spring 155 to rock the latch 152 into its position illustrated in Fig. 2. In this position, the latch overlies the foot 158 of lever 136 and thus prevents the latter from being 65 rocked into printing contact with the paper during a printing operation. However, when any 70 75

idler gear 141 is rotated to its "1" or any other position, its cam slot 154 will rock the associated latch outwardly, enabling the associated lever 136 to be subsequently rocked into printing position.

For the purpose of printing all zeros to the right of the lowest significant digit, each of the latches 152 is provided with an ear 160 overlying the corresponding ear on the lever to the left. Therefore, when any latch is rocked outwardly by its gear 141, all of the latches 152 to the right thereof will likewise be rocked outward to free their respective printing lever 136 even though the dials associated therewith register zero.

However, in accordance with the present invention, the accumulator and printer are split, enabling the two leftmost or highest orders to be used for item counting only, independently of the remaining orders. Therefore, the ear 160 of the latch 152 associated with the highest order of the value accumulating section is cut off as shown at 160a so that rocking of the two highermost order latches 152 will have no effect upon the remaining latches.

Accumulator

The accumulator is of the two directional, subsequent transfer type and is disclosed in detail in Figs. 4, 5 and 6.

The accumulator comprises in general a pair of parallel shafts 86 and 87, both rotatably mounted in bearings formed in a series of ordinarily spaced brace plates 10b rigidly held in spaced relation to each other by suitable interlocking combs 11b well known in the art.

The shaft 86 carries the hereinbefore mentioned accumulator element gears 85 and the shafts 86 and 87 are guided for vertical movement in slots, one of which is shown at 94 (Fig. 8) formed in machine side plates at opposite sides of the machine, one being shown partially at 24.

Since each gear 85 comprises ten teeth, it will move through one tooth space during each increment of advance of its associated drive rack 19.

As each gear 85 moves through one revolution or ten tooth spaces as a result of accumulating ten digits, it conditions a transfer mechanism to subsequently enter one digit into the gear 85 of the next arithmetically higher order to the left. For this purpose, a transfer pawl 150 is provided, being capable of rotating its associated gear an increment of one tooth space in either direction, depending on the type of operation being performed.

Each pawl 150 surrounds its associated gear 85 and is pivoted at 1150 on a cam follower lever 160 pivotally supported on the lower shaft 87. Lever 160 is provided with a roller 161 adapted to be engaged and moved by an aligned one of a series of transfer cams 180 arranged in a helical path on a transfer shaft 30 as shown in Fig. 9.

The pawl 150 is provided with three detents 170, the central one of which is normally engaged by the roller 119a of a centralizer lever 119 pivoted on a stud 20 attached to the associated brace plate 10 and pressed against the pawl by a spring 121 extending between the centralizer and a second stud on the brace plate so as to normally hold the pawl in its central position shown in Fig. 4 wherein it is ineffective to cause a transfer. The centralizer 119 is also adapted to hold the pawl 150 in an additive transfer condition shown in Fig. 5 or a subtractive transfer condition (not shown) in which the lower detent of the pawl would be engaged thereby. Also, the

centralizer normally maintains the pawl in its rearward position shown in Figs. 4 and 5 wherein the lever 160 rests against the adjacent comb 11a, the centralizer being capable of returning the pawl to such position after a transferring operation.

A centralizer pawl 32 is also pivoted on each stud 20 and is spring pressed against the respective gear 85 to yieldably locate the same in any of its ten possible locations.

Each gear 85, as it rotates in a counter-clockwise direction from its "9" position (not shown) to its "0" position illustrated in Figs. 4 and 5 during an additive operation, carries a tooth 23 attached integrally thereto into engagement with an ear 24 formed on the pawl 150 which is located in the next arithmetically higher order, thus rocking the pawls downwardly about its pivot 1150 toward its additive transferring position shown in Fig. 5. As the pawl approaches its lowermost position, the centralizer 119 becomes effective to fully move the pawl thereinto.

In the fully conditioned position of pawl 150, a transfer tooth 28 thereon is located directly behind a tooth of the associated gear 85 so that in a subsequent transfer phase in which the cams 180 are rotated through a complete revolution, the cam follower arms 160 are rocked to advance the pawls 150. Thus the tooth 28 will engage and drive the gear 85 one tooth space in a counter-clockwise or additive direction.

Likewise, during a subtractive operation, and when an accumulator gear 85 rotates clockwise from a "0" position to a "9" position the tooth 23 thereof will strike the ear 24 of the associated transfer pawl, moving the latter into an upper position. Thereupon, a transfer tooth 28a on the pawl is positioned opposite a tooth near the bottom of gear 85 so that when the pawl 150 is subsequently moved forward during the transferring phase the transferring tooth will advance the gear one tooth space in a subtractive direction.

It should be noted that during additive, subtractive and totalling operations, the accumulator will be disengaged from the racks i. e. it will be returned to its neutral position as shown in Fig. 2, prior to the transfer phase which occurs late in the machine cycle. Therefore, at the end of the digitizing phase of the cycle, the pawls 150 in all orders which are to receive a tens transfer will be conditioned or located in an upper or lower position depending on the type of operation, and the gears will be completely demeshed from the racks 19.

It will be recalled that the accumulator is split to form, in effect, two separate accumulators. In this case the two highermost orders of the machine are reserved for the item counting feature. For this purpose, the transfer tooth 23 on the gear associated with the third highest order gear 85 is cut off as shown at 23a in Fig. 6 to render the gear 85 of this order ineffective to cause a transfer to be made into the item counter section.

Machine controls

The various mechanisms of the machine are driven by a cyclically operable shaft 51, Figs. 2, 7, 8 and 9, which is driven by an electric motor (not shown) through a gear 56, the latter being selectively connected to the shaft 51 through a cyclic clutch generally indicated at 57. The latter is controlled by a clutch dog 58 pivoted at 59 and so arranged to clutch the shaft 51 to the drive gear 56 when the clutch dog is rocked

counter-clockwise from its position in Fig. 7. The clutch dog is connected by a pin and slot connection 227 to a clutch control bar 228 supported for a longitudinal movement by a pair of parallel links 229 pivotally supported on frame pins 230. A spring 228a normally maintains the bar 228 in a rearward position shown in Fig. 7 to hold the dog 58 in clutch disengaging position. The bar 228 has four cam slots 231 formed therein, each of which underlies a pin 232 carried on a lever 233 pivoted on a frame pin 234 and urged upwardly by a tension spring 235. The various pins 232, underlie the subtract, tax, sub-total and total bar stems 13, 14, 18 and 17, respectively. Therefore, depression of any of these bars will cause the associated pin 232 to cam the clutch control bar 228 forwardly to effect engagement of the clutch 57.

Provision is also made to effect engagement of the clutch upon depression of such other bars as the front add bar 10 (Fig. 2). The key stems 10a of the add bar 10 have openings therein embracing a rod 160 secured to arms 161 carried by a rockable shaft and spring urged in a counter-clockwise direction to normally hold the add bar 10 in its illustrated raised position. The rod 160 also overlies a cam surface 249 (Fig. 7) on the forward end of bar 228 so that depression of the add bar 10 will cause the rod 160 to move down over the cam surface and thus move the bar 228 forwardly, thereby to cause engagement of the clutch.

Accumulator positioning controls

As mentioned hereinbefore, the accumulator is raised or lowered to mesh the accumulator gears 85 with upper or lower rack gear sections of the drive racks, depending upon the type of operation to be performed. For this purpose, mechanism is provided which is under control of the different control bars for determining and effecting the positioning of the accumulator.

Referring to Fig. 8, the accumulator shaft 86 has a pair of rollers, one of which is shown at 97, rotatably mounted on opposite ends thereof and each is embraced by a cam groove 98 formed in a box cam 94 which is pivoted on a frame stud 95. Suitable means (not shown) is provided to transfer movement from the cam 94 shown in Fig. 8 to the like cam at the opposite end of the accumulator. Clockwise rocking of the cam 94 will lower the accumulator into its subtractive position while counter-clockwise rocking thereof from its illustrated position will raise the accumulator to its additive position.

The cam 94 carries a pair of pins 257 and 258 arranged on the opposite sides of the frame pin 95. These pins are adapted to be selectively engaged by a hook member 259 connected to a three arm cam follower 260 which is pivoted on the shaft 81. The cam follower is urged counter-clockwise by a spring 261 to press a roller 263 on another arm thereof against a cam 264 keyed on the drive shaft 51. Cam 264 has a high portion extending over substantially half of its periphery whereby to rock the cam follower 260 and thereby to move the hook member 259 rearward and hold it in a rearward position during approximately the first half of the machine cycle. Normally, during additive operations or when the machine is at rest, the hook member 259 is raised by tension spring 265 whereby a slot 266 therein embraces the upper pin 257 so that as the hook is moved rearward it will rock the cam 94 clockwise to raise the accumulator into its additive position.

For the purpose of locating the hook member 259 in a lowermost position, a control bar 267 is provided, being supported for longitudinal movement by a pair of parallel links 268 pivotally supported on frame pins 269. The bar 267 has three camming surfaces formed thereon and underlying the aforementioned pins 232 which are operable by the subtract bar 13, the sub-total bar 18 and the total bar 17. The bar 267 is connected by a pin and slot connection 271 to a bellcrank 272 pivoted at 273 and having a pin 274 on the opposite end thereof which is embraced by a slot formed in the hook member 259.

The camming surfaces 270 of the bar 267 are so arranged that upon depression of any of the bars 13, 18 or 17, the control bar 267 will be moved forwardly to cause bellcrank 272 to lower the hook member 259 until a slot 275 therein will embrace the pin 258 so that subsequent rearward movement of the hook member will place the accumulator into its lower or subtractive position.

It will be noted that no camming surface is provided on the bar 267 in association with the pin 232 of the tax bar 14 so that depression of the latter will not disturb the additive setting of the accumulator conditioning mechanism.

During an additive or subtractive operation and after the high portion of the cam 264 has passed the roller 263, which occurs before the return of the drive racks, the spring 261 will become effective to return the hook 259 to its foremost position (as shown in Fig. 8) and thereby locate box cam 94 in its neutral position to likewise return the accumulator into its neutral position shown in Fig. 2. A centralizer lever 276 pivoted at 277 is spring urged into engagement with the lower edge of the cam 94 to centralize the same in its neutral position.

In totalling operations, the accumulator is returned to zero during the first part of the operating cycle and is then placed in a neutral position before return of the racks in the same manner as normal addition and subtraction operations, while in sub-totalling operations the accumulator is returned to zero during the first part of the cycle and is then again reset at its former accumulated value during the latter part of the cycle. Therefore, it is necessary in the latter operation to maintain the accumulator in mesh with the drive racks 19 until the latter have returned from their forward strokes. To this end, a second cam 279 is mounted on the shaft 51 adjacent the cam 264 and is provided with a high portion around the greater part of the periphery thereof. This cam engages a roller 280 mounted on the lower end of a second bellcrank 281 also pivoted on shaft 81 and urged counter-clockwise by a spring 1285.

A slot 282 is formed in a rearwardly extending arm of bellcrank 281 and lies coextensive with a slot 283 formed in the cam follower 260. However, it will be noted that the slot 282 is somewhat shorter than the slot 283. A pin 284 carried by a link 285 rides within one or both of the slots 282 and 283, depending upon the position of the link longitudinally of the machine. The link 285 is connected to the lower end of the lever 233 associated with the sub-total bar 18. Thus, when the bar 18 is in its raised ineffective position shown in Fig. 8, the pin 284 will lie solely in the slot 283 of cam follower 260 and the cam 264 will be effective to control positioning of the accumulator. However, upon depression of the

bar 18, the pin 284 will be moved forwardly to locate within both the slots 282 and 283. In this condition, i. e., during a sub-totalling operation, the two followers 260 and 281 will move as a unit and the cam 279 will therefore, through the hook member 259, hold the accumulator engaged with the drive racks 19 throughout both their forward and return strokes.

Referring to Figs. 4 and 5, a series of ordinarily spaced stop levers 286 are keyed on the shaft 87 and during totalling and sub-totalling operations, are rocked into blocking positions relative to zero locating ears 287 carried by the associated accumulator gears 85.

The zero stop levers 286 are rocked into blocking position by power under control of the bars 17 and 18, and in order to accomplish this an arm 288 (Fig. 8) is keyed to the shaft 87 and is connected through a pin and slot connection 289 to a floating lever 290 which rides on the stationary frame pin 277 and is connected at its forward end to the link 292, the upper end of which is connected to a cross link 293 intermediate its ends. The link 293 is pivotally connected to the pins 232 under lying the bars 17 and 18. Thus, upon depression of either of the bars, the link 292 will be lowered sufficiently to rock lever 290 counter-clockwise about the pin 277 to position a shoulder 294 thereon in the path of a pin 295 carried by the bellcrank 281. Now, when the bellcrank is rocked at the beginning of a total or sub-total operation the pin 295 will drive the lever 290 forwardly, rocking the shaft 87 against the action of a spring 291 to likewise rock the levers 286 into blocking position.

Means not shown are provided to retract the various zero stops 42 (Fig. 2) upon depression of the total and sub-total control bars. Thus, as the machine continues its cycle, the racks will be driven forward, rotating the accumulator gears 86 in a subtractive direction until they are stopped in zero positions by contact of the ears 287 on gears 85 with the levers 286. The racks will therefore stand in positions mechanically representing the value previously registered by the accumulator and will consequently cause the the printer dials to register this value.

Symbol printing

In order to indicate on the paper tape the type of factor or value being printed, an appropriate symbol is printed alongside each value which is the result of a total, sub-total, tax entry or subtract operation.

Referring to Fig. 7, a symbol controlled rack 324 is provided having two elongated slots 325 and 180b, the former guided over a frame stud 327 and the latter embracing the shaft 81. A spring 328 urges the rack forwardly against the aforementioned rack drive shaft 70. A series of shoulders 330 are formed on the rack and each is adapted to engage a control bar actuated pin 232 upon depression of its respective control bar. The shoulders 330 are spaced apart distances somewhat greater than the distances between the pins 232 so as to enable a forward movement of the rack a differential amount dependent upon the particular key depressed.

A rack gear section 331 on the rack 324 meshes with a gear 332 carried by a shaft 117, the latter forming part of the aforementioned idler assemblies 178 and having a second gear 181 (Fig. 2) fastened thereto. The latter meshes with one of the idler gears 141 which is entrained with an associated symbol printing dial 135 forming part

of a printer dial assembly. The latter is similar in all respects to the various numeral dial assemblies described hereinbefore except that symbol type appropriate to the type of operation being performed are formed on the periphery of the dial in place of the numeral characters. Also, there is no ear 160 formed on the latch 152 for this dial assembly.

Means are provided for preventing the symbol rack 324 from advancing when an addition operation is being performed, it being desired not to print a symbol during such addition operation. For this purpose, a latch 334 (Fig. 7) is pivoted on a frame stud 335 and is urged clockwise into latching engagement with a pin 336 on the rack 324 by a spring 340 (Fig. 8) tensioned between a pin 337 on the latch 334 and the pin 232 associated with the sub-total control bar 18. The pin 337 fits in a notch 338 formed in the accumulator positioning control bar 231. Therefore, upon an adding operation initiated by the add bar 10, the bar 267 will not move and hence, the latch 334 will remain in latching position to prevent a substantial movement of the symbol rack at that time. However, during subtraction, total and sub-totalling operations, the bar 267 will be actuated by the respective control bar and the latch 334 will consequently be raised against the action of its spring 340 to permit the rack 324 to follow the rack drive shaft 70 until stopped by the depressed pin 232 so as to register the printing mechanism accordingly.

Tax entry

As mentioned hereinbefore, a tax entry bar 14 is provided for entering tax, duty and the like items set up on the amount keys 9. It will be noted on reference to Figs. 7 and 8 that the tax bar initiates operation of the machine in the same manner as the other bars 13, 17 and 18 since the pin 232 underlying the same is adapted to actuate the clutch control bar 228 to cause engagement of the cyclic clutch 57. Also, there is no connection between the tax bar and the accumulator conditioning control bar 257 and consequently the hook member 259 will be allowed to remain in its additive control position shown in Fig. 8 to effect an additive entry of any tax item.

However, the tax bar effects printing of an appropriate symbol as shown at 350 (Fig. 10) even though it has no control over the bar 267. For this purpose, a cam slide 351 is pivoted on the pin 337 of latch 334 and is provided with a guide slot 352 which guides over the hub 353 of the lever 233 cooperating with bar 14. The pin 232 of the aforementioned lever 233 overlies a camming surface 270a of the slide so that depression of bar 14 will force the slide 351 forwardly to remove the latch 334 (Fig. 7) from latching engagement with the pin 336 on the symbol control rack 324, enabling the latter to move forward until the second shoulder 330 from the left strikes the tax bar controlled pin 232 whereby to register the symbol printing device to print the tax symbol.

Item counting

According to the present invention and as stated hereinbefore, the machine is arranged to count the number of items additively entered into the machine by splitting the accumulator and printer into two sections, reserving the two arithmetically highermost orders for item counting. Such item counting, in which the unit 1 is entered

11

into the item counter section of the accumulator during each additive machine operation in which an item value is entered is effected by a false tens transfer operation initiated into the units order of the counter section. The machine is arranged to render such entry ineffective if the entry is a tax item and/or if a machine operation of the additive type is made without an item set up on the keyboard.

For this purpose, an arm 300 (Figs. 6 and 9) is fixed on a rockable shaft 301 and is arranged with an ear 299 thereof in alignment with the transfer pawl 150a of the units order of the counter section. Also fixed on shaft 301 is a bellcrank 302, the assembly thus formed being normally held clockwise against the crossrod 81 by a spring 303 extending between the bellcrank 302 and a second bellcrank 305 freely rotatable on the shaft 301. The latter has a camming surface 306 which extends in the path of a pin 307 carried by a disc 308 which is fixed to the aforementioned cyclic drive shaft 51.

On the lower end of lever 305 is pivoted a bellcrank 309, one end of which is connected to the bellcrank 302 by a yieldable link assembly 310. The latter comprises a pair of overlapping links 311 and 312 connected to the bellcranks 302 and 309, respectively. A pair of studs 313 extend from the former link through an elongated slot 314 in link 312, and a spring 315 is tensioned between one of said studs and a pivotal connection between the link 312 and bellcrank 309 to normally hold the link assembly in the collapsed condition shown in Fig. 9. The other end of bellcrank 309 is connected by a link 316 to a bail 317 pivoted on a cross shaft 318.

The flange 319 of the bail 317 extends across the machine and under those racks 19 which are associated with the item value entering orders only of the accumulator. The racks 19 have shoulders 320 which, when said racks are in their zero or home positions (shown in Figs. 2 and 9), are located slightly to the rear of the flanges 319, permitting the bail to be rocked counter-clockwise of its illustrated position. However, when any of said racks is moved forward one or more increments, its shoulder 320 will move over the flange 319, preventing subsequent rocking movement of the bail.

It will be noted that the aforementioned arrangement for sensing the entry of an item value into the machine does not impose any load upon either the keys 9 or the racks 19.

As mentioned hereinbefore, during an additive operation, the accumulator will be raised to mesh the accumulator gears 85 with the rack gear sections 83 (Fig. 2) of the racks 19. Consequently, the tens transfer pawls 150 will be likewise raised, while in neutral positions shown in Fig. 4, to positions indicated by the dot and dash lines 150' of Fig. 9. If during such additive operations an item has been entered into the keyboard, one or more of the racks 19 will have advanced forwardly, blocking the bail 317 from rocking counter-clockwise. Thus, during rotation of the cyclic shaft 51, the pin 307 will strike the cam surface 306 of the bellcrank 305, rocking the same clockwise and, since the bellcrank 309 is prevented from rocking the bail 317, the latter bellcrank will rock counter-clockwise relative to the bellcrank 305, drawing link assembly 311 down to rock the shaft assembly including shaft 301 and arms 300 and 302 counter-clockwise from their illustrated positions. Therefore, the ear 299 of arm 300 will move from its full line position to

12

its lowered position indicated by the dot and dash lines 299', and in doing so will strike the transfer pawl 150a in the units order of the counter section of the accumulator, setting the same in an additive transfer condition. Consequently, during the subsequent transfer phase, the unit one will be entered into the counter section. It should be understood that the spring 315 is materially stronger than the spring 303 and is thus normally effective to overcome the latter when the link assembly 310 is drawn downwardly.

In the event that an additive operation is initiated without an item being entered into the keyboard, all of the racks 19 will consequently be held in their home positions. As the bellcrank 305 is rocked clockwise by pin 107, the bail 317 will be rocked counter-clockwise since the spring 303 is effective to hold bellcrank 302 and arm 300 in their upper non-effective positions. In such positions, the transfer pawl 150a will be allowed to remain in its neutral position.

In order to prevent an item count of a tax item entered into the machine, a blocking segment 360 is fixed on the aforementioned shaft 117 (see also Fig. 7) controlling the position of the symbol printing dial. During a tax entry operation the symbol printing control rack 324 is rocked to advance to such a position that the shaft 117 will position the segment 360 in blocking relation to an ear 361 on the arm 300. Thus, the arm 300 will be blocked from moving sufficiently to set the transfer pawl 150a into a transferring position, the spring 315 yielding at this time to allow expansion of the link unit 310.

During subtract, totalling and sub-totalling operations the accumulator will be lowered into a subtractive position below that indicated by the full lines in Fig. 9 and consequently, even though the arm 300 is rocked counter-clockwise to its transfer initiating position, the arm will be ineffective to move sufficiently to engage transfer pawl 150a and therefore no item count will ensue.

Upon a totalling or sub-totalling operation initiated by the control bars 17 or 18, respectively (Fig. 1), the total of the item count will be printed to the left of the total of the item values as indicated at 365 (Fig. 10).

In the machine disclosed herein to which the item counting and tax entry mechanisms are applied, the leftmost row of amount keys 9, as received in Fig. 1, are aligned with and control the drive rack 19 associated with the units order of the item counting section of the accumulator. In order to prevent inadvertent depression of any of the keys in this row, a cap 8a is placed over the entire row.

It should be noted that more or less of the various orders of the machine may be apportioned to the item counting device by suitably locating the arm 300 along shaft 301 between the particular orders at which the split is to occur and arranging the particular gear 85 containing the mutilated ear 23a in the highest order of the item value accumulating section.

Although I have described my invention in detail in its preferred form and therefore have utilized certain specific terms and languages herein, it is to be understood that the present disclosure is illustrative rather than restrictive, and that changes and modifications may be made without departing from the spirit or scope of the claims appended hereto.

Having thus described our invention, what we

13

desire to secure by United States Letters Patent is:

1. In a cyclically operable calculating machine, the combination of an item value accumulator, differentially operable actuating mechanism therefor, an item counter, means for entering a unit into said item counter, power means, an operating device operable by said power means, said operating device having two output connections operable differentially with respect to each other, one of said connections being normally operable idly and arranged to be blocked by said actuating mechanism upon operation thereof, and the other of said connections being inoperable upon said idle operation of said first mentioned connection and arranged to cause operation of said unit entering means upon blocking of said first mentioned connection.

2. In a cyclically operable calculating machine, the combination of an item value accumulator, differentially operable actuating mechanism therefor, an item counter, means for entering a unit into said item counter, power means, an operating device operable by said power means, said operating device having two output connections movable differentially with respect to each other, one of said output connections being normally movable idly and arranged to be blocked by said actuating mechanism upon operation thereof, the other of said connections being arranged to cause operation of said unit entering means upon blocking of said first mentioned connection, and yieldable means for normally blocking said other connection.

3. In a cyclically operable calculating machine, the combination of an accumulator divided into an item value accumulating section and an item counting section, differentially operable actuating mechanism for said accumulator, mechanism for moving said accumulator into operative relation to said actuating mechanism, means for entering a unit into said item counting section, power means, an operating device operable by said power means, said operating device having two output connections movable differentially with respect to each other, one of said connections being normally movable idly and arranged to be blocked by said actuating mechanism upon operation thereof, the other of said connections being arranged to cause operation of said unit entering means only in response to said movement of said accumulator, and yieldable means for normally blocking said last mentioned connection.

4. In a cyclically operable calculating machine, the combination of an item value accumulator, differentially operable actuating mechanism therefor, an item counter, means for entering a unit into said item counter, a differential device comprising a power operated lever arranged to fulcrum about either of two points, means controlled by said actuating mechanism upon operation thereof for causing said lever to fulcrum about one of said points, means operably connected to said lever at the other of said points and operable upon movement of said lever about said first mentioned point to cause operation of said unit entering means, and yieldable means normally causing said lever to fulcrum about said second mentioned point.

5. In a cyclically operable calculating machine, the combination of an item value accumulator, actuating mechanism therefor including racks differentially movable from home positions, an item counter, means for entering a unit into said

14

item counter, power means, and a device operable by said power means, said operating device having two output connections operable differentially with respect to each other, one of said connections being normally operable idly and arranged to be blocked by any of said racks upon movement thereof from said home position thereof, and the other of said connections being inoperable upon said idle operation of said first mentioned connection and arranged to cause operation of said unit entering means upon blocking of said first mentioned connection.

6. In a cyclically operable calculating machine, the combination of an item value accumulator, actuating mechanism therefor including racks differentially movable from home positions, an item counter, means for entering a unit into said item counter, an operating device including a lever, power operated means for actuating said lever at one point thereon, a fulcruming device operatively connected to said lever at a second point thereon and arranged to normally move idly therewith, said fulcruming device being arranged to be blocked by any of said racks upon movement from the home position thereof whereby to fulcrum said lever about said second point, an actuating device operatively connected to said lever at a third point and arranged to cause operation of said unit entering means upon blocking of said fulcruming device, and means normally yieldably causing said lever to fulcrum about said third point.

7. In a calculating machine, the combination of an item value accumulator, actuating mechanism therefor including differentially movable racks; means for moving said accumulator into operative relation to said racks, an item counter, means for entering a unit into said item counter, and means for controlling said unit entering means including a sensing device movable through a predetermined path and adapted to be blocked from moving through said path by any of said racks upon movement thereof, and means operatively connected to said sensing device and operable only upon blocking of said sensing device for causing operation of said unit entering means.

8. In a cyclically operable calculating machine, the combination of actuating mechanism including differentially operable racks, an item value accumulator movable in one direction into an operative relation to said racks to additively receive items therefrom, said accumulator being movable in another direction into another operative relation to said racks to subtractively receive items therefrom, an item counter movable with said item value accumulator, a device movable with said item value accumulator for entering a unit into said item counter, and a controller for said device, said controller having a stroke of a predetermined amount and being effective to engage and control said device when said item value accumulator is in said first mentioned operative relation, said controller being ineffective to engage said device when said item value accumulator is in said other operative relation.

9. In a calculating machine, the combination of an accumulator divided into an item accumulating section and an item counting section, actuating mechanism including differentially operable racks for said accumulator; means for selectively moving said accumulator into an operative relation to said racks to additively receive items therefrom and for moving said ac-

cumulator into another operative relation to said racks to subtractively receive items therefrom, a device movable with said accumulator for entering a unit into said item counting section, and a controller for said device, said controller having a stroke of a predetermined amount and being effective to engage and control said device when said accumulator is in said first mentioned operative relation, said controller being ineffective to engage said device when said accumulator is in said other operative relation.

10. In a cyclically operable calculating machine, the combination of actuating mechanism including differentially operable racks, an item value accumulator movable in one direction into an operative relation to said racks to additively receive items therefrom, said accumulator being movable in another direction into another operative relation to said racks to subtractively receive items therefrom, an item counter movable with said item value accumulator, a device movable with said accumulator for entering a unit into said item counter, an actuator for said device, said actuator having a stroke of a predetermined amount and being effective to engage and actuate said device when said item value accumulator is in said first mentioned operative relation, said actuator being ineffective to engage and actuate said device when said item value accumulator is in said other operative relation, drive means for said actuator including a sensing device movable through a predetermined path and adapted to be blocked from moving through said path by any of said racks upon movement thereof, and means operatively connected to said sensing device and operable only upon blocking of said sensing device for causing operation of said actuator.

11. In a cyclically operable calculating machine, the combination of an item value accumulator, differentially operable actuating mechanism therefor, an item counter, means for entering a unit into said item counter, power means, an operating device operated by said power means, said operating device having two output connections movable differentially with respect to each other, one of said connections being normally operable idly and arranged to be blocked by said actuating mechanism upon operation thereof, and the other of said connections be-

ing inoperable upon said idle operation of said first-mentioned connection and arranged to cause operation of said unit entering means upon blocking of said first-mentioned connection, and means for selectively disabling said last-mentioned connection.

12. In a cyclically operable calculating machine, the combination of an item value accumulator, actuating mechanism therefor including differentially operable racks, an item counter, means for entering a unit into said item counter, a device for operating said unit entering means comprising a member, means pivotally supporting said member, means for rocking said member about said pivotal supporting means, a bell crank having two arms, means pivotally supporting said bell crank intermediate said arms on said member at a point spaced from said first-mentioned pivotal supporting means, a fulcruming device pivotally connected to one of said arms, and arranged to normally move idly therewith upon rocking of said member, said fulcruming device being arranged to be blocked by any of said racks upon movement thereof whereby to fulcrum said bell crank about said pivotal connection, and an actuating device operatively connected to the other of said arms and arranged to cause operation of said unit entering means upon fulcruming of said bell crank about said pivotal connection.
